[57] **CLAIM**

The ornamental design for an electronic automobile routing system for storing and retrieving travel instructions and information, as shown and described.

DESCRIPTION

FIG. 1 is a front elevational view of an electronic automobile routing system for storing and retrieving travel instructions and information, showing my new design; FIG. 2 is a rear elevational view thereof; FIG. 3 is a top view thereof;

FIG. 4 is a left side elevational view thereof;

FIG. 5 is a right side elevational view thereof;

FIG. 6 is a bottom view thereof; and,

FIG. 7 is a reduced front perspective view thereof.

The broken line showing of the indicia appearing on the display is for illustrative purposes only and forms no part of the claimed design.
